GOBLET BUFF

Edwin F. Doyle, Amityville, N. Y., assignor to
 Barker Brothers, Inc., Brooklyn, N. Y., a corporation of New York

Application June 22, 1948, Serial No. 34,487

18 Claims. (Cl. 51—193)

1

My invention relates to improvements in goblet buffs or buffing wheels adapted to be used in buffing the inside of hollow objects which cannot be buffed with conventional type buffs, and to a method of constructing the improved buff.

Goblets and other hollow objects made of various metals, plastics and other materials cannot be buffed satisfactorily with the conventional type of disc-shaped buffing wheel. I therefore provide an improved buff having a polishing surface on its end as well as on its peripheral base. One form of buff in accordance with my invention and which is particularly adapted for the polishing of cup-shaped objects has a substantially hemispherical-shaped end adapted to substantially fit the inner surface of cup-shaped objects such as goblets and similar articles.

An important feature of my invention is the provision of an improved goblet buff made of fabric material consisting of woven threads in which the fabric material is arranged in such a way that the ends of the threads essentially make up the entire polishing surface of the buff. In such a construction, sheets of fabric material are arranged so that the threads extend at different and varying angles to the spindle or axis of the buff.

In accordance with my invention I construct a goblet buff of improved function by an improved procedure including the assembling of a stack of circular fabric discs, one upon the other to provide a unitary base section. The thickness of this stack may, as an example, be from one-third to one-half the diameter of the discs. This stack of discs is sewed together tightly by making a ring of stitches concentric with the axis of the stack, for example at a position about one-half the radius of the discs. Prior to sewing, the stack of discs is preferably punched to provide a hole through the axis of the stack of discs. Inside the ring of stitches a cylindrical or other shaped cavity is cut through approximately one-half or less of the discs, concentric to their axes, the cavity for example having a diameter of about one-third that of the discs, or formed so that its inner peripheral wall is somewhat inside the circle of stitching. A series of perforations is then made inside the cavity around the axis of the stack through the bottom section below and within the cavity wall. As an example, six or seven perforations regularly distributed around the base of the cavity outside the axis of the stack of discs, are provided.

This structure provides a unitary base section for the buff upon which to mount other discs in

2

such a way as to provide a substantially hemispherical or other shaped end or top to the buff. This end is formed by stacking a plurality of fabric discs of substantially the same diameter as the discs used in making the base section. This latter stack of discs may have from about one-third to one-half the thickness of the base section, and it is provided with a concentric hole and surrounding perforations which match the axial hole and perforations of the base section.

The discs of the second stack or end section are not sewed together but are advantageously left unsewed and are laced to the bottom section by the use of twine or other suitable sewing cord which is threaded through the circle of holes in the two sections or stacks. When the lacing is completed, the twine or cord is pulled through tightly from below so that the upper stack of fabric discs is pulled into the cavity in the upper portion of the lower stack of discs. This results in the deformation of the discs of the upper stack so that their peripheral edges ripple and fold upwardly toward the extended axis of the buff to form a buff end portion having a substantially spherical shape.

In a modified form of construction, a portion of the fabric discs used to make the end of the buff is perforated with a circular row of perforations or holes between the regular row of perforations and the periphery of the discs, and a lace is run through this outer circle of perforations and finally used in the manner of a drawstring to ruffle the end discs regularly and provide a firm structure on the end portion of the buff. Other forms are described hereinafter.

It will be understood that the invention is not restricted to the making of a buff of a particular size or one having an exactly hemispherical-shaped end. The end of the buff may be made according to the article to be buffed so that the end is flat, oval or conical shaped, by using different size discs and by shaping the buff after the end section or sections have been pulled into and secured into the cavity in the base section of the buff. The buff may have a base section which includes a substantially cylindrical outer surface which merges into the periphery or base of an approximately hemispherical or other end section.

My invention includes other features and advantages which are described in detail herein-after in connection with the accompanying drawings forming a part of this application and which illustrate particular embodiments of the invention.

In the drawings:

Fig. 1 is a perspective view showing the base section of the buff in its initial stages of manufacture after a stack of similar fabric discs has been sewed together.

Fig. 2 is a view similar to that of Fig. 1, partly broken away, showing subsequent steps in the formation of the base of the buff.

Fig. 3 is a perspective view of a stack of discs used in forming the top or end of the buff.

Fig. 4 is a vertical sectional view showing the processed stacks of fabric discs of Figs. 2 and 3 in spaced relation and illustrating the method of lacing.

Fig. 5 is a top view of the assembly shown in Fig. 4 with the lacing partly tightened down.

Fig. 6 is a vertical sectional view similar to that of Fig. 4, showing the completed buff with central portion of the stack of fabric discs illustrated in Fig. 3 completely pulled into the base section shown in Fig. 2.

Fig. 7 is a top view illustrating one possible form of configuration of the edges of the fabric discs of the finished buff.

Fig. 8 is a bottom view of the finished buff shown in Fig. 7.

Fig. 9 is a bottom view similar to that of Fig. 8 but of a modified form of buff illustrated in Figs. 10, 11 and 12.

Fig. 10 is a vertical sectional view similar to that of Fig. 4, illustrating a modified form of buff construction with the various sections in spaced relation at the stage when the lacings are in place but not drawn up.

Fig. 11 is a view similar to that of Fig. 10 at a later stage of the process illustrating particularly the effect of tightening the outer lacing in the end section, Figs. 10 and 11 being taken respectively on the lines 10-10 and 11-11 of Fig. 12.

Fig. 12 is a top view of the assembly shown in Fig. 10, showing the way in which the top section of the buff is ruffled and stiffened.

Fig. 13 is a vertical sectional view similar to that of Fig. 6 of a modified form of completed buff constructed in accordance with the present invention in which a number of separate stacks of discs are assembled on a base section.

Fig. 14 is a view similar to that of Fig. 2 showing the construction of the features of the base section of the buff shown in Fig. 13.

Figs. 15 and 16 are perspective views, respectively, of stacks of discs used in making the buff shown in Fig. 13.

Figs. 17, 18 and 19 are top views, respectively, of stacks of discs similar to those shown in Figs. 3, 15 and 16, but modified by including various shaped cut-outs as shown, for the purpose of removing some of the material from the inner portion of the discs.

Referring to the drawings, the steps of the method of constructing the improved buff in accordance with the features of the present invention may be conveniently described in connection with the different views of the drawings. For example, in making a buff such as is illustrated in Fig. 6, having a unitary base section 15 which is substantially cylindrical in form and combined with an end section which is substantially hemispherical, the base section 15 for the buff is started by stacking a pile of similar fabric discs 16. As an example, discs 16 of a woven cotton fabric material such as a good grade of unbleached muslin, having a diameter of about two and one-half inches may be used for a particular size of buff. The discs of the stack 15 as

shown in Fig. 1, are stitched tightly together with heavy cord stitching 17 to form a circular row of stitches concentric to the discs. The stack 15 is also punched with a suitable device to provide an axial hole 18 entirely through the stack, this hole in the lower part of the stack being used for receiving the point of a tapered spindle, not shown, on which the buff is mounted for use in polishing.

10 The compacted and stitched stack of discs made by the foregoing steps comprises a single piece blank of relatively simple structure for the base of the buff, which is later modified and used to provide the base section for the buff, regardless of the shape of the end section of the buff. It will be understood that where dimensions or shapes are given they are illustrative only and not intended to limit the scope of the invention. The base section of the buff or the blank, however, has a generally flat cylindrical shape made up of the superposed circular layers of fabric, the edges of which make up a substantially cylindrical peripheral polishing surface which blends gradually into the end portion of the finished buff.

15 The next step in the process is shown in Fig. 2, in which the stitched stack of fabric discs shown in Fig. 1 and forming the base blank, has been formed into a buff base 19 by cutting into the 20 stitched stack, a cylindrical-shaped concentric cavity or hole 20 of relatively large diameter but somewhat within the circular row of stitches 17. This cavity 20 is cut only approximately half-way through the stack of discs and the uncut 25 portion below and within the perimeter of the cavity is punched with a circular row of holes or perforations 21 for the reception of a lacing cord or twine. The holes 21 are advantageously cut in the shape shown by a star cutter or punch, all 30 holes being preferably punched simultaneously. If desired, the holes 21 may be cut prior to the cutting of the cylindrical-shaped cavity 20, but fewer layers of discs 16 must be punched if the 35 holes are made after the cavity 20 has been cut. 40 The base section 19 of the buff is now complete 45 and ready for assembly with the end section.

The end section 22 of the buff is made up, as shown in Fig. 3, by assembling a plurality of similar fabric discs 23, one on top of the other, and 50 punching an axial hole 24 corresponding to the hole 18, and a circular series of holes 25 corresponding to the circular row of holes 21.

The next step of the process comprises the lacing of the sections shown in Figs. 2 and 3 in 55 the position shown in Fig. 4. As illustrated, a doubled cord 26 of the type of the brown sewing cord used by upholsterers is laced through the holes 21 and 25 by using, for example, a large needle and successively passing the doubled cord 60 26 upwardly and downwardly through successive ones in the assembled base and end sections, as shown in Fig. 4. A top view of the lacings is 65 shown in Fig. 5. At first the doubled cord 26 is put in loosely, and then it is drawn up tightly from the bottom so as to pull the central portion of the end section 22 of the buff engaged by the 70 doubled cord 26 into the cylindrical cavity 20 to provide approximately the structure shown in Fig. 6 of the drawings.

75 In a more particular sense the lacing together of the end and base sections of the buff as described above is effected by knotting two ends of the cord 26 as at 28 in Fig. 8, and starting the cord through one of the holes 21, as shown, from the bottom. The cord is then brought through

the adjacent hole to the left, through the loop provided by the knot 28, and then down through the hole 21, to the right of the knot. The cord is then brought through the successive holes 21 and 26 and finally brought out through the bottom of the buff through the hole 21 to the left of the knot 28. The doubled cord 26 is then pulled up until it is tight, and the central portion of section 22 of the buff is pulled fully down to the bottom of the cavity 20, as shown in Fig. 6. The free end of the doubled cord 26 is then looped through one of the previous lacing loops and knotted at 30, so that the sections of the buff are held tightly together.

It will be seen that according to the showing in Figs. 6 and 7, the sheets of the stack of fabric sheets 23, forming the end section of the buff, fold in upon each other to provide a substantially solid end of oval or hemispherical shape, while the base section 19 provides a substantially cylindrical-shaped portion for the buff. A sufficient number of fabric discs are used in the end section, as shown in Fig. 3, to provide a volume of fabric which will make a comparatively solid end section and a firm buffing or polishing surface. Furthermore, the threads of the fabric discs extend toward the peripheral surface of the buff from positions generally adjacent the axis of the buff. In a more particular sense, the threads of the discs of the end section of the buff extend radially from the position of the lacing cord 26 so that for the most part, the polishing surface of the buff is made up of the ends of the threads of fabric used in making the buff.

Considering the position of the spindle or shaft, upon which the buff is mounted, as for example a shaft having a tapered and threaded end engaging the axial hole 18, it will be seen that the polishing surfaces of the buff are parallel to the axis of the hole 18 or of the spindle inserted therein, and at a constantly changing angle to that axis. The relationship may be stated in another way, the layers of fabric in the base of the section are at right angles to the hole 18, while the surfaces of the fabric forming the oval end of the buff vary from parallel to the axis of the buff, to perpendicular. Fig. 7 illustrates in a diagrammatic sense the manner in which the fabric discs in the end section of the buff fold in to provide the oval or substantially hemispherical polishing surface.

The modified form of buff shown in Figs. 9 to 12 includes a base section 40 made up in the same way as the base section 15 shown in Fig. 2, and an intermediate end section 42 made up in the same way as the end section 22 shown in Fig. 3. The modified form of the buff includes an end section 44 which is made up in the same way as the end section 22 shown in Fig. 3 except that it is also provided with a series of punches or holes 46 formed in a circular series about midway between the inner circular series of holes 47 and the periphery of the fabric discs. A draw-string cord 48 is laced through the holes 46.

The modified form of buff is assembled in the manner shown in Fig. 10 by means of the doubled cord 50 which is laced through the holes in the sections 40, 42 and 44 as in Fig. 4. These three sections are then drawn together so that the central portions of the two end sections 42 and 44, the portions of them adjacent the cord 50, are pulled into the cylindrical cavity 52 in the section 40 and tightly secured therein by drawing up the cord or twine 50 in the manner de-

scribed above in connection with Fig. 6 of the drawings.

After the cord 50 is drawn up and knotted, the draw-string cord 48 is then drawn up, Fig. 11 showing the position of the section 44 after the cord 48 is partly drawn up. When finished, the draw-string cord 48 is drawn up as tightly as possible so that the fabric discs of the end section 44 are folded substantially uniformly in and out in wave fashion to make a very compact oval end section for the buff in cooperation with section 42. The cord 48 is knotted and the ends of the cord clipped off so that the knot is invisible, leaving the buff having an end approximately the same shape as that shown in Figs. 6 and 7, except for a greater degree of regularity of the wave-like folds. Means other than the draw-string may be used to fasten the discs of section 42 together. It will be seen from the showing in Fig. 11 that the fabric discs alternately fold in and out, or are ruffled in and out, according to the positions of the sections of the cord 48, and that when the cord 48 is drawn up tight the discs will not be straightened out by centrifugal force when in use.

When the buff section 42, shown in Figs. 10 and 11, has its central section pulled into the cylindrical cavity 52, it will assume approximately the position of the end section shown in Fig. 6, except that of course the layers of fabric of the section 42 will ruffle and fold to fill in between the base section 40 and the extreme end section 44.

The modified form of buff construction shown in Fig. 13 is made up by about the same series of steps as that employed in making the buffs shown in Figs. 6 and 11, the buff including a base section 54 like that illustrated in Fig. 14, which comprises a stack of discs sewed together by a circular row of vertical stitches 55. As in the case of the base section 19, the base 54 is made up of a pile or stack of assembled discs, after which it is cut partly through to form a cavity 56, which is relatively large compared to the diameter of the discs, that is, proportionately larger than cavity 20 shown in Fig. 2. The base section 54 has an axial hole 57 for receiving a spindle and is punched to provide three sets of punch holes 58, 59 and 60 in concentrically arranged circles, these holes extending through the bottom portion of the base 54 as in the case of the holes 21 in Fig. 2. The inner circle of holes 58 correspond to the holes 21.

As seen in Fig. 13, the upper portion of the buff includes three separate stacks of discs 61, 62 and 63 which are drawn into the cavity 56 and laced to its bottom. The outer stack of discs 61 is shown in Fig. 15, prior to assembly, and as being stitched and having a central cavity 64 of a diameter somewhat smaller than the diameter of the cavity 56. The stack 61 also includes a circular row of holes 60a which match the holes 58 in the base section 54. The second stack of discs is shown in Fig. 16 before assembly. It is stitched and includes a central cavity 65 and a circular row of holes 59a which match the holes 59 in the base 54. The stack of discs 63 is not separately shown but may be like the stack of discs 22 shown in Fig. 3, where the row of holes 25 correspond to the row of holes 58 in the base 54.

In making up the buff as illustrated in Fig. 13, the three stacks of discs 61, 62 and 63 are assembled successively in the manner illustrated in Fig. 4 by the use of a lacing cord 66 for the stack 61, a lacing cord 67 for the stack 62 and a lacing cord 68 for the stack 63. The cord 66 is advan-

stageously drawn up first, so as to tightly lace the inner portion of the stack 61 in the cavity 56 of the base 54 in the manner shown in Fig. 13. The inner portion of the stack 62 is then pulled into the cavity 64 of the stack 61 so as to bring it down onto the bottom of the cavity 56. Thereafter the stack 63 is pulled down into the cavity 65 of the stack 62, by the cord 68, onto the bottom of the cavity 56. The cords 66, 67 and 68 are then tied in the manner illustrated above in connection with Figs. 8 and 9. While the cords shown in Fig. 13 are illustrated as single cords, they may be doubled, and the lacings and knots made in the same manner as that illustrated in Figs. 4 to 12.

It will be noted that while the cavity 56 extends only partly through the base section 54, the cavities 64 and 65 are illustrated as extending entirely through the stacks 61 and 62, respectively. These latter cavities 64 and 65 need not extend entirely through the respective stacks, but may extend only part way through, while the bottom portions of stacks 61 and 62 within the cavities may be provided with one or more circular rows of holes corresponding to and approximately matching the holes 58 and 59.

For some types of buff it is extremely important to have a buff with an unusually firm end portion. I have found that this object may be attained by providing the end stacks of discs with a construction such as illustrated in Figs. 17, 18 and 19. Fig. 17 shows a stack of discs 70 having a central cavity 71 for receiving the central portion of another stack of discs, and a circular row of holes 72 for receiving a lacing cord such as the cord 67, for pulling the stack of discs into a cavity in a base section, or into a cavity in a stack of discs mounted on a base section, as illustrated in Fig. 13. The stack of discs 70 is provided with a circular row of regularly spaced large circular holes 73 between the row of holes 72 and the perimeter of the discs. The holes 73 are cut through the superposed discs of the stack of discs 70 for the purpose of removing some of the material from the completed inward portion of the buff. The presence of the large holes 73, as illustrated, permits the stack of discs to be drawn into the central cavity more easily than otherwise would be the case, and at the same time provides an end buff section which is more firm than otherwise would be the case. The holes 73 allow the central portion of the stack of fabric layers to fold or ruffle more easily than if they were solid, while the full volume of the fabric discs is retained immediately adjacent the surface of the buff.

Fig. 18 shows a modified form of a stack of superposed fabric discs 75 having a central cavity 16, a circular row of lacing holes 77 and a series of regularly spaced relatively large square holes 78 which correspond to and have the same function as the circular holes 13 of Fig. 17.

Fig. 19 shows a further modified form of construction in which a stack of superposed fabric discs 80 is provided with a central cavity 81, a circular row of lacing holes 82 and a circular row of regularly spaced large holes or cut-outs 83 of triangular shape, serving essentially the same purpose as the cut-outs or holes 13 and 78.

While the discs or stacks of discs shown in Figs. 17, 18 and 19 correspond approximately to the stack of discs shown in Fig. 16, it is to be understood that they may correspond to the stack of discs 61, shown in Fig. 15, and therefore form the first stack in Fig. 13, or correspond to the stack of discs 22 shown in Fig. 3, and therefore correspond to the last stack of discs 63 shown in Fig. 13, or to

the end stacks 22, 42 and 44 of Figs. 4 to 12. The shape of the cut-out holes or openings in the discs shown in Figs. 17, 18 and 19 are merely illustrative, it being understood that other shapes may be provided and furthermore that in any one stack of discs it is not essential that the cut-out holes, as for example 73, 78 and 83 match the other holes in the superposed discs, since the primary purpose of these holes is to remove some of the material from the inward portion of the buff to facilitate assembly of the stacks of discs into the central cavity or cavities and to make the outer portion of the buff relatively more firm.

The buff illustrated in Fig. 13 may be made up of stacks of discs in which the alternate discs or multiples of discs are respectively solid and provided with holes or cut-outs, such as 73, 78 and 83.

In describing the various modifications of the buff illustrated in the drawings, the central cavities have been shown as being cylindrical or circular in shape, but it will be understood that these cavities may have other shapes, as for example, they may be square or have any convenient number of sides.

The improved method of making the goblet buff of the present invention accomplishes its end with a minimum number of steps. For example, the base sections are made from one-piece blanks composed of superposed fabric discs sewed together as a unit. The sewed blanks are thereafter cut to provide a central cavity such as the cavity 20 in Fig. 2, or the cavity 56 in Fig. 14. The making of the base sections of the buffs in this way reduces the number of steps and avoids the handling of more than a single base element.

While a fiber twine or cord is preferably used for assembling the sections of the buff, it will be understood that the sections may be clamped together by wire or rivets, or other suitable means.

Non-metallic fastening means such as the cord referred to is preferred because of its flexibility in threading through the lacing holes and in drawing the sections of the buff together.

The fabric discs, of which the buff of the present invention is made, are preferably made of fairly coarse cotton yarn but other fiber fabrics may be employed. Goblet buffs made in accordance with the present invention are of relatively soft flexible material and the outer portions are sufficiently flexible that they have the quality of shaping themselves substantially to the inside shape of the object to be polished. In addition to fastening the sections of the buff by the means referred to above they may be fastened together by machine or hand-sewn, by cement or by a combination of these means. The fabric material around the axial hole in the base of the buff is advantageously saturated with some cement or plastic material in solution so that it will be sufficiently rigid to hold the threads of the spindle or shaft on which the buff is mounted for use.

What I claim is:

1. The method of constructing a goblet buff having an oval-shaped end, comprising assembling a stack of similar fabric discs, providing an axial hole through the stack of discs, firmly securing the stack of discs together by means of a circular series of securing means extending through all of the discs about mid-way between the axial hole and the periphery of the stack, cutting a cylindrical cavity in the assembled stack axially of the hole and inside the securing means to a depth approximating one-half the depth of the stack, forming a circular series of holes within the confines of the cylindrical cavity extending

parallel to said axial hole and opening through the bottom of said cavity, assembling a second stack of fabric discs having a diameter approximately the same as the discs of the first stack and providing therethrough a circular series of holes matching the holes in the first stack, positioning the second stack over the cavity of the first stack lacing a cord through the series of holes of the two stacks of discs so that each section of the cord extends through both stacks, and thereafter tightening the laced cord and pulling the central portion of the second stack of discs into the cavity in the first stack of discs, thereby causing the second stack of discs to ruffle and fold into a structure providing an oval exterior surface forming the end of the buff.

2. The method of constructing a goblet buff having an oval-shaped end comprising, assembling a stack of similar fabric discs firmly securing the stack of discs together by means of a circular series of stitches extending through all of the discs between the axis and the periphery of the stack, cutting a cylindrical cavity in the assembled stack axially thereof and inside the stitches, forming a circular series of holes within the confines of the cylindrical cavity extending parallel to the axis of the stack and opening through the bottom of said cavity, assembling a second stack of fabric discs and providing therethrough a circular series of holes matching the holes in the first stack positioning the second stack over the cavity of the first stack, lacing a cord up and down through the series of holes of the two stacks of discs so that each section of the cord extends through both stacks, and thereafter tightening the laced cord and pulling the central portion of the second stack of discs into the cavity in the first stack of discs, thereby causing the second stack of discs to ruffle and fold into a structure providing an oval exterior surface forming the end of the buff.

3. The method of constructing a goblet buff having an oval-shaped end, comprising assembling a stack of similar fabric discs, providing an axial hole through the stack of discs, firmly binding the stack of discs together, cutting a cylindrical cavity in the assembled stack axially of the hole and inside the securing means to a depth approximating one-half the depth of the stack, forming a circular series of holes within the confines of the cylindrical cavity extending parallel to the axis of said axial hole and opening through the bottom of said cavity, assembling a second stack of fabric discs having a diameter approximately the same as the discs of the first stack but without securing such discs together and providing therethrough a circular series of holes matching the holes in the first stack, positioning the second stack over the cavity in the first stack, lacing a cord through the holes of the two stacks of discs so that each section of the cord extends through both stacks, and thereafter tightening the laced cord and pulling the central portion of the second stack of discs into the cavity in the first stack of discs, thereby causing the second stack of discs to ruffle and fold into a structure providing an oval exterior surface forming the end of the buff, said second stack of discs being of sufficient volume to form a tightly packed oval end structure.

4. The method as defined by claim 3 in which an outer circular series of holes is provided in a plurality of discs at the extreme end portion of the second stack, passing a draw-string cord through said outer holes in series, and tightening

said draw-string cord to fold in the discs of the extreme end portion into a circular wave-like configuration.

5. The method of constructing a goblet buff having a substantially hemispherically-shaped end, comprising, providing a substantially cylindrical base section for the buff having a concentrically located substantially cylindrical cavity extending from about one-third to about one-half way through the base section, providing a stack of similar fabric discs approximating in thickness about one-half that of the base section, forming a circular series of holes parallel to the axes of and through the base and stack in matching relationship, the holes in the base section being within the confines of the periphery of said cavity, passing a lacing cord in and out in series through the circular series of holes of said stack and base section, and drawing up the cord tightly and thereby

10 20 25 pulling the central section of said stack into the cavity in the base section whereby said stack of fabric discs are caused to ruffle and fold into positions on said base forming a firm substantially hemispherically shaped end polishing surface therefor.

6. The method of constructing a goblet buff having a substantially hemispherically-shaped end, comprising, providing a substantially cylindrical base section for the buff having a concentrically located substantially cylindrical cavity extending from about one-third to about one-half way through the base section, said base section

30 35 40 being made up of cloth discs bound together, providing a stack of similar fabric discs, forming a circular series of holes parallel to the axes of the base section and stack in matching relationship, the holes in the base being within the confines of the periphery of said cavity, inserting a binding means through the holes of said stack and base section, and pulling the central section of said stack into the cavity in the base section whereby

45 said stack of fabric discs are caused to flair outwardly from the base and to ruffle and fold into a position on said base forming a substantially hemispherical end therefor.

7. The method of constructing a goblet buff having a substantially hemispherically-shaped end comprising, providing a substantially cylindrical base section for the buff having a con-

50 55 60 centrically located substantially cylindrical cavity extending thereto, providing a first stack of similar fabric discs for the end of the buff, providing a second stack of similar fabric discs for an intermediate section of the buff, forming a circular series of holes parallel to the axes of the base section and of said stacks in matching relationship through said base section and stacks, the holes in the base section extending through the floor of and being within the confines of the per-

65 70 75 ipery of said cavity, providing a circular series of holes through the discs of the first stack outside the first series of holes, lacing a draw-string cord up and down through the outer series of holes, arranging the second stack over the cavity

side of the base section and the first stack over the second stack in matching relationship, inserting a binding means through the holes of said stacks and base sections, pulling the central portions of said stacks into the cavity in the base section

75 whereby the discs of said stacks are caused to flair outwardly and forwardly from the base and to ruffle and fold into a position on said base forming a substantially hemispherical end therefor, drawing up the cord in the first stack and thereby forming the peripheral edges of the discs

11

thereof into a circular wave-like configuration at the end of the buff.

8. A goblet buff having an end polishing surface substantially hemispherical in shape, comprising a base section formed of superposed flexible fabric discs bound together, a plurality of superposed fabric discs bound to said base section by securing means extending through their central areas, said last-named fabric discs having a circular series of matching holes extending through them inwardly of their peripheral edges, a draw-string cord extending serially through the circular series of holes and drawn up tightly thereby holding the involved discs in a ruffled circular wave-like formation at the end of the buff.

9. A goblet buff having base and end sections as polishing surfaces, said buff being made up of an assembly of flexible fabric discs of substantially similar diameter in which the discs in the base section of the buff are approximately at right angles to the axis of the buff, the end section of the buff including a series of piles of fabric material each except the last pile having a central cavity into which the central portion of the succeeding pile is held.

10. A goblet buff as defined by claim 9 in which the piles of fabric material are made up of fabric discs some of which have cut-out portions inward of their peripheral edges.

11. A goblet buff as defined by claim 9 in which at least one of the piles of material have a series of regularly spaced holes through the pile spaced from its axial center.

12. A goblet buff having an end polishing surface, comprising a base section made up of a stack of superposed fabric discs, said stack of fabric discs having a central cavity in the top thereof, a second stack of fabric discs having a central cavity and mounted with its central portion secured in the cavity in the base section, and a third stack of fabric discs extending over said second stack and having its central portion secured in the cavity of the second stack.

13. A goblet buff as defined by claim 12 in which at least one of the stacks above the base section includes fabric discs having relatively large spaced holes between the cavity in the stack and the periphery of the discs.

14. The method of constructing a goblet buff having an end polishing section, comprising providing a substantially cylindrical base section for the buff having a concentrically located cavity, extending thereto, providing a first stack of fabric discs for the end of the buff, providing a second stack of similar fabric discs for an intermediate section of the buff, said second stack having a central cavity smaller than the cavity in the base, forming a circular series of holes parallel to the axes of the base section and of said stacks in matching relationship through said base section and second stack, the holes in the base section extending through the floor of and being within the confines of the periphery of the cavity therein, providing a circular series of holes through the discs of the first stack and base section inside the first series of holes in the base, arranging the second stack over the cavity side of the base section in matching relationship, inserting a binding means through matching series of holes in the second stack and base section, pulling the central portion of the second stack into the cavity in the base section, arranging the first stack over the second stack with its series of holes in matching relation with the 75

12

inner series of holes in the base section, inserting a binding means through the holes in the first stack and base section, and pulling the central portion of the first stack into the cavity in the second stack of discs.

5 15. The method of constructing a goblet buff having an end polishing surface, comprising providing a fabric base section for the buff having a concentrically located cavity extending part 10 way through the base section, providing a stack of similar fabric discs of sufficient thickness to form the end section for the buff, arranging said stack over the cavity-side of the base section, inserting a binding means through the central portion of the stack and base section within the periphery of the cavity, and pulling the central section of said stack into the cavity in the base section and securing it there, whereby said stack of fabric discs are caused to ruffle and fold into positions on said base forming a firm end polishing surface.

15 20 25 16. The method defined by claim 15 including the step of providing relatively large holes in at least some of the discs of said stack between their central areas and their periphery.

17. A goblet buff comprising a base portion and an end portion, the base portion including superposed flexible fabric discs bound together in substantially parallel arrangement with their edges providing a polishing surface, the end portion including a plurality of fabric discs having their central portions superposed in substantially parallel arrangement, means extending through the superposed central portions of the discs of the end section and securing the end section to the base portion, and a draw-string cord woven through at least a portion of the discs forming the end section and holding the outer portions of said discs into a ruffled circular wave-like formation.

30 35 40 45 50 55 18. A goblet buff having an approximately hemispherically-shaped end section for polishing the inside of cup-shaped objects, said buff including a plurality of similar fabric discs secured together and arranged so that the polishing surface of the buff is almost entirely made up of the ends of the threads of which the discs are woven, said arrangement including folded and ruffled fabric discs at one end of the buff having surfaces approximately parallel to the axis of the buff, and a draw-string cord passing serially through a circular series of holes extending through said folded and ruffled fabric discs inwardly of their peripheral edges and holding them in a circular wave-like formation.
